UNITED STATES PATENT OFFICE.

R. B. ANGUS, OF TREMONT, PENNSYLVANIA.

IMPROVED MOLD FOR CASTING THROTTLE-VALVES.

Specification forming part of Letters Patent No. 57,062, dated August 14, 1866.

To all whom it may concern:

Be it known that I, R. B. ANGUS, of Tremont, Schuylkill county, State of Pennsylvania, have invented a new and useful Improvement in the Manufacture of Throttle-Valves; and I do hereby declare that the following is a full, clear, and exact description thereof, which will enable others skilled in the art to make and use the same, reference being had to the accompanying drawings, forming part of this specification, in which—

Figure 1 represents a longitudinal central section of this invention, the line $z z$, Fig. 3, indicating the plane of section. Fig. 2 is a horizontal section of the same, taken in the plane indicated by the line $x x$, Fig. 1. Fig. 3 is a similar section in the plane indicated by the line $y y$, Fig. 1.

Similar letters of reference indicate like parts.

This invention relates to a flask made for the purpose of casting throttle-valves. Said flask is composed of a cylinder bored out to the diameter of the seat into which the valve has to fit, and provided with suitable blocks, the inner ends of which, when properly put together, form the mold for the valve to be cast. Said blocks are held in position by a screw-clasp, so that they can be screwed up as the metal shrinks, and a suitable hole passing transversely through the cylinder allows of introducing the pin or rod which forms the core for the axle of the valve in such a manner that the hole for the axle is cast in and a valve is obtained, which is ready to be put in its

seat immediately upon being removed from the mold.

A represents a cylinder, made of iron or any other suitable material, and bored out to correspond to the seat or tube into which the valve is to be fitted. This cylinder is provided with two blocks, B C, the inner ends of which are so shaped that the same, when properly put together, form the mold for the valve to be cast, as clearly shown in Fig. 1 of the drawings. A hole, a , which passes transversely through the cylinder A, allows of introducing the core b for the purpose of producing the hole for the axle of the valve.

The blocks B C are held in position by a screw-clamp, D, as clearly shown in Fig. 1, and the screws $c d$ serve to screw up the blocks as the metal shrinks. Suitable channels e serve to admit the molten metal, and other channels, f , allow the air from the mold to escape.

By these means a throttle-valve can be cast which requires no fitting and which is ready to be put in its seat immediately as it comes from the mold.

What I claim as new, and desire to secure by Letters Patent, is—

The blocks B C and screw-clamp D, in combination with the cylinder A, all constructed and operating substantially as and for the purpose described.

R. B. ANGUS.
